Patented May 22, 1917.

UNITED STATES PATENT OFFICE.

WILLIAM J. BEST, OF DETROIT, MICHIGAN, ASSIGNOR TO GAS OIL STOVE COMPANY, OF DETROIT, MICHIGAN, A CORPORATION OF MICHIGAN.

HYDROCARBON-BURNER.

1,227,239.

Specification of Letters Patent. Patented May 22, 1917.

Application filed December 8, 1915. Serial No. 65,654.

To all whom it may concern:

Be it known that I, WILLIAM J. BEST, a citizen of the United States, and a resident of Detroit, in the county of Wayne and State 5 of Michigan, have invented a new and Improved Hydrocarbon-Burner, of which the following is a specification.

This invention relates to burners for alcohol and the heavier liquid hydro-carbons 10 such as kerosene, and its object is to provide a burner wherein the parts will long retain their shape and wherein maximum heat will be produced by the fuel.

This invention consists in the details of 15 construction shown in the accompanying drawing and particularly pointed out in the claims:

In the drawings, Figure 1 is a central vertical section of my improved burner. Fig. 2 is an elevation of the parts constituting the inner chimney and the trough. Fig. 3 is a plan of the upper section of the inner chimney. Fig. 4 is a plan of the lower section of the inner chimney. Fig. 5 is a section of 25 the lower ends of the chimneys and the trough.

Similar reference characters refer to like parts throughout the several views.

In the accompanying drawing the inner chimney is shown to be formed of three sections 1, 2 and 3, the upper section being closed by means of a top 4. The upper end of the lower section is preferably drawn with an inwardly extending radial flange 5 having an opening 6 to permit air to pass into the middle and upper sections. This flange 5 is formed with a ledge 7 adapted to receive the flange 8 of the intermediate section. The intermediate section is formed 40 with a head 9 to which the head 10 of the upper section may be secured in any desired manner, and these two heads are formed with an opening 11 to permit air to pass into the upper section. Each of the three sections is provided with a series of holes 12 through which air may pass into the space between the sections, the hole 11 in the heads 9 and 10 controlling the amount of air which may pass into the upper section. The amount of 45 air passing through the holes 12 in the lower and intermediate sections is preferably somewhat in excess of that necessary

for the combustion of the hydro-carbon fuel, and therefore the amount of air necessary at the openings 12 of the upper section may 55 be relatively small.

Integrally formed on, welded or brazed to the lower end of the lower section 1 is a trough 14, best shown in Fig. 5, having a flange or shoulder 15 to center the asbestos 60 wick 16, and an inclined portion 17 that joins the part 1 of the inner chimney. The trough is also formed with a second circumferential shoulder 18 that is adapted to properly center the perforated outer chimney 19. A ledge 20 and cylindrical flange 65 21 complete the trough into which the feed pipe 22 connects.

A cover 24 for the trough has a flange 25 that is preferably brazed to the flange 21 on the ledge, an inclined portion 26, and a flange 27 that fits around the outer chimney. A small hood or cowl 28 is secured to the outer chimney and extends down over the upper end of the flange 27, being separated 75 therefrom a sufficient distance to permit a current of air to pass below its lower edge, thence up between it and this flange 27 and then through the holes 29 in the outer chimney, carrying with it any fuel vapors that 80 may escape between this flange 27 and the outer chimney.

A shell or drum 31 surrounds the outer chimney and has small brackets 32 secured to its inner face that rest on the cover of the trough. When it is desired to light the burner, a small amount of fuel is permitted 85 to flow to the trough through the pipe 22, and after saturating the wick 16, is lighted by means of a small ball of cotton on the end 90 of a wire which ball may be saturated with alcohol, or the fuel may be ignited by removing the drum 31 and outer chimney 19.

By reason of the flange 5 and the heads 9 and 10 of the several sections of the inner chimney, these sections are substantially prevented from warping out of shape, and because of this, the proper flame can be secured even after the burner has long been in service. The ledge 20 being integral with 100 the inner chimney it will become quite hot, and the fuel from the pipe 22 will be volatilized and flow around the outer chimney, entering the space between the chimneys

through the holes 34, then be ignited from the wick 16 and burn, air entering in proper amounts through the holes in the chimneys.

The details and proportions of this burner 5 may all be changed by those skilled in the art without departing from the spirit of this invention.

I claim:—

1. In a hydro-carbon burner, the combination of perforated outer and inner chimneys and a trough integral with the inner chimney and supporting the outer chimney, means to feed fuel to the trough, an annular cover for said trough having a flange at its 15 inner edge extending up around the outer chimney, and a cowl secured to the outer chimney and extending down over said flange but spaced therefrom, said outer chimney having holes between the flange and 20 the cowl to permit air to enter the space between the chimneys.

2. In a hydro-carbon burner, the combination of perforated outer and inner chimneys and a trough integral with the inner chimney and supporting the outer chimney, means to feed fuel to the trough, an annular cover for said trough having a flange at its 25 inner edge extending up around the outer chimney, a cowl secured to the outer chimney and extending down over said flange but spaced therefrom, said outer chimney having holes between the flange and the cowl to per-

mit air to enter the space between the chimneys, and holes below the flange to permit fuel gas to enter said space from the trough. 35

3. In a hydro-carbon burner, an inner chimney consisting of a plurality of sections, two of the sections having integral heads secured together and perforated to permit the passage of air. 40

4. In a hydro-carbon burner, an inner chimney consisting of three sections, the upper and intermediate sections having heads secured together and perforated to permit the passage of air, a cover for the upper section, the lower section having an annular flange to support the other sections. 45

5. In a hydro-carbon burner, an inner chimney consisting of three sections, the upper and intermediate sections having integral heads secured together and perforated to permit the passage of air, the lower section having an annular flange to support the other sections. 50

6. In a hydro-carbon burner, an inner chimney consisting of a plurality of sections and a partition wall in said inner chimney integral with one of said sections, the adjacent section being formed with an inwardly extending flange resting on said partition. 55

In testimony whereof I sign this specification.

WILLIAM J. BEST.
